CLAIM

The ornamental design for a motion assisting device, as shown and described.

DESCRIPTION

FIG. 1 is a front elevational view of a motion assisting device showing our new design;

FIG. 2 is a rear elevational view thereof;

FIG. 3 is a top plan view thereof;

FIG. 4 is a bottom plan view thereof;

FIG. 5 is a right side elevational view thereof, the left side elevational view being a mirror image of the right side elevational view shown; and,

FIG. 6 is another front elevational view thereof showing a use state.

The outline of the partial human body shown in broken lines shown in FIG. 6 is for the purpose of illustrating an environment of use of the motion assisting device and forms no part of the claimed design. The remaining broken lines that show portions of the motion assisting device also form no part of the claimed design.
